US00D988223S

(12) **United States Design Patent** (10) Patent No.: **US D988,223 S**
Mora et al. (45) Date of Patent: ** Jun. 6, 2023

(54) **WHEEL PROTECTOR**(71) Applicant: **1Lss, Inc**, Los Angeles, CA (US)(72) Inventors: **Fernando Mora**, Reseda, CA (US);
Alejandro Baca, Sherman Oaks, CA (US); **Mydul R. Islam**, Los Angeles, CA (US); **Kevin H. Vuong**, Baldwin Park, CA (US)(73) Assignee: **1Lss, Inc**, Los Angeles, CA (US)(**) Term: **15 Years**(21) Appl. No.: **29/868,904**(22) Filed: **Dec. 15, 2022**(51) LOC (14) Cl. **12-06**

(52) U.S. Cl.

USPC ..... **D12/213**(58) **Field of Classification Search**USPC D12/114, 115, 204–215, 217, 223

(57) **CLAIM**

The ornamental design for a wheel protector, as shown and described.

DESCRIPTION

FIG. 1 is a front, bottom perspective in the environment of an unclaimed wheel of a wheel protector according to one embodiment of the invention.

FIG. 2 is a front, top, right side perspective of a wheel protector of FIG. 1.

FIG. 3 is a rear, bottom, left side perspective view of the wheel protector of FIG. 1.

FIG. 4 is a front elevation view of the wheel protector of FIG. 1.

FIG. 5 is a rear elevation view of the wheel protector of FIG. 1.

FIG. 6 is a left side elevation view of the wheel protector of FIG. 1.

FIG. 7 is a right side elevation view of the wheel protector of FIG. 1.

FIG. 8 is a top plan view of the wheel protector of FIG. 1; and,

FIG. 9 is a bottom plan view of the wheel protector of FIG. 1.

The broken lines shown in the drawings are for environmental purposes only and form no part of the claimed design.
